UNITED STATES PATENT OFFICE.

GEORGE G. SEYMOUR, OF TROY, NEW YORK.

VALVE FOR FLUSHING-TANKS.

No. 878,094.

Specification of Letters Patent.

Patented Feb. 4, 1908.

Application filed March 30, 1906. Serial No. 302,840.

To all whom it may concern:

Be it known that I, GEORGE G. SEYMOUR, a citizen of the United States, residing at Troy, county of Rensselaer, and State of New York, have invented certain new and useful Improvements in Valves for Flushing-Tanks, of which the following is a specification.

The invention relates to such improvements and consists of the novel construction and combination of parts hereinafter described and subsequently claimed.

Reference may be had to the accompanying drawings, and the reference characters marked thereon, which form a part of this specification.

Similar characters refer to similar parts in the several figures therein.

Figure 1 is a vertical longitudinal section 20 of a flushing tank provided with my improved valve mechanism. Fig. 2 is a view in front elevation, with the cap or dome removed, of my improved valve shown on a larger scale. Fig. 3 is a central vertical section of the valve. Fig. 4 is a horizontal section of the same taken on the broken line 4-4 in Fig. 3. Fig. 5 is a vertical section taken on the broken line 5-5 in Fig. 3. Fig. 6 is a cross-section taken on the broken line 6-6 in Fig. 3. Fig. 7 is a plan view of one end of the float-arm. Fig. 8 is an edge view of the same. Fig. 9 is a plan view of the upper end of the valve-operating lever.

The principal object of the invention is to increase the durability and efficiency of valves, particularly those adapted for use in connection with flushing tanks to control the inlet thereto.

Other objects of the invention will appear in connection with the following description:

Referring to the drawings wherein the invention is shown in preferred form, 1, represents a valve-plug of frusto-conical form adapted to fit a similarly formed seat in the shell, 2, shown mounted upon a pipe coupling, 3, adapted to have connected therewith a water pipe 4. The shell, 2, has below its frusto-conical seat a cylindrical extension, 5, forming a slideway for a depending spider-formed stem, 6, on the valve-plug, which plug also has an upward stem-extension, 7, adapted to fit and reciprocate in a slideway, 8, in the superposed cap or dome, 9, which has its lower end screwed into a ring, 10, mounted upon the coupling, 3, by means of the posts 11. The slideways,

5 and 8, serve to guide the valve plug in its opening and closing movements and prevent it from tipping, while leaving it sufficiently free to accurately engage its seat. 60

The valve is operated by means of an angle-lever, 12, fulcrumed at 13, upon a pair of ears, 14, on the coupling, 3, having its inner horizontal end bifurcated to receive and extend part-way around the shell, 2, as 65 shown in Fig. 4. The ends of the bifurcated end-portion of the lever, 12, which are on diametrically opposite sides of the shell, 2, are connected by the respective links, 15, with the opposite ends of a cross-head, 16, 70 on the upwardly extended valve-stem, 7, whereby, when said lever is rocked, movements are transmitted to said valve along substantially vertical lines. Any known means may be employed for operating the 75 lever 12.

My improved valve is especially adapted for use in flushing tanks, and in Fig. 1, I have shown it so used, the lever, 12, being connected with the arm, 17, of a float 18. The 80 manner of connecting the float, 18, with said lever may be varied to adapt the valve for use in tanks of different depths. In a low shallow tank the arm, 17, of the float is connected directly with the upper end of the lever, 12, as shown in Fig. 3. When the valve is employed in connection with a deep tank, I provide an extension, 19, for the vertical arm, 17, of the float with the upper end of said extension as shown in Fig. 1. I have 90 shown a preferred form of non-rotating connection between the float-arm and said lever in Figs. 6, 7, 8 and 9, one of the connecting members being formed with a lateral projection, 20, and the other with a laterally 95 opening seat or recess, 21, adapted to receive said projection, both the projections and the seat being similarly serrated and the members being held together by a screw 22. When the members are bound together by 100 the screw, 22, rotation of one member upon the other is rendered impossible. Adjustment is permitted however, by removing the screw, separating the two members and reassembling them in proper position. 105

When the extension, 19, is employed, the connection of its lower end with the upper end of the lever, 12, and of its upper end with the arm, 17, of the float is accomplished in the manner just described. 110

In Fig. 1, I have shown the flushing tank provided with an ordinary hollow lift-valve,

23, for the outlet of the tank, said lift-valve being adapted to be operated by the lever 24. In the use of flushing tanks, it is desirable to provide for a slight flow of water through 5 the outlet pipe after the outlet valve is closed and while the tank is filling, in order to render certain the proper sealing of the trap in the bowl after the siphonic action which accompanies the discharge of the contents of the bowl has been overcome. For 10 this purpose I have provided a small pipe, 25, leading from the dome, 9, to a point above the open upper end of the hollow outlet valve 23. As the tank is filling, the 15 valve, 1, being open, the inflow of water is directed into said dome with considerable pressure sufficient to force a stream of water upwardly through the pipe, 25, from which it is discharged down through the hollow outlet valve, 23, and outlet pipe, 26, to the bowl. 20

What I claim as new and desire to secure by Letters Patent is

In a valve, the combination with a frusto-conical valve-seat, and slideways above and below said seat; of a frusto-conical valve-plug having projections from its opposite ends occupying said slideways throughout the movement of the valve to and froth its seat; a lever having a bifurcated end; and a pair of links separately connected, each at its lower end to one arm of the bifurcated lever, and at the other end to said valve-plug intermediate of its end-projections. 25

In testimony whereof, I have hereunto set my hand this 28th day of March, 1906.

GEORGE G. SEYMOUR.
